UNITED STATES PATENT OFFICE

161,079

FRONT FOR AN OPHTHALMIC MOUNTING

Doris A. Atwood, West Newton, Mass.

Application January 24, 1949, Serial No. 442

Term of patent 14 years

(Cl. D57—1)

To all whom it may concern:

Be it known that I, Doris A. Atwood, a citizen of the United States, residing at West Newton, in the county of Middlesex and State of Massachusetts, have invented a new, original, and ornamental Design for a Front for an Ophthalmic Mounting, of which the following is a specification, reference being had to the accompanying drawings, forming part thereof in which Fig. 1 is a front view of a front for an ophthalmic mounting, showing my new design.

Fig. 2 is a section on the line 2—2, Fig. 1.

My design for a front for an ophthalmic mounting is characterized by the representation of a jeweled crown surmounting the bridge portion and of the specific type as shown on the drawing.

The essential features of my design for a front for an ophthalmic mounting reside in the portions shown in full lines.

I claim:

The ornamental design for a front for an ophthalmic mounting, as shown and described.

DORIS A. ATWOOD.
